Claims priority, application Great Britain
August 31, 1951

6 Claims. (Cl. 139—134)

This invention relates to looms and more particularly to improved means for producing the shuttle motion, known as the picking mechanism.

It is well known that the majority of the noise in a normal loom is due to the impact between the picker and the shuttle and due to another impact between the shuttle and the swells which bring the shuttle to rest at each end of the slay or shuttle race-board. The need for these violent impacts is due to the need to accelerate the shuttle to a velocity high enough to carry it with certainty through the shed, and to destroy this high velocity when the pick or shuttle travel from one end of the slay to the other, is completed. Moreover the shuttle must be accelerated to and decelerated from this high velocity over a short distance, and consequently the numerical value of shuttle acceleration is very high indeed.

In order to overcome these disadvantages it is necessary to reduce the numerical value of shuttle acceleration and deceleration by the maximum possible amount.

In practice this means that the shuttle must continue to accelerate until it reaches a point midway through the shed, and having reached that point it must then decelerate for the remainder of its travel, which condition in turn imposes the need for the shuttle to be under control at all times during its travel to and fro across the slay, even when it is between the two layers of warp threads known as the shed.

It has been proposed to produce a shuttle motion having these conditions by magnetically controlling the shuttle in accordance with a mechanically oscillated traveller, the shuttle being mounted on wheels running on the slay of the loom. The rate of work of a loom with a magnetically controlled wheeled shuttle is, however, limited by practical considerations. The total magnetic flux linking the shuttle with the mechanical oscillatory traveller must be large and this means the use of heavy and cumbersome magnets in the traveller and in the shuttle. Limitations are thus imposed on the amount of shuttle accelerating force available on the value of maximum shuttle acceleration and on the mean shuttle velocity. Because of the weight of the magnets in the shuttle and the force of the magnetic linkage, the resistance of the wheels on the slay is high and results in mechanical losses and damage to the warp threads.

It is the object of the present invention to provide a loom having an improved means of shuttle motion which will reduce the noise of operation to a minimum, will permit the use of relatively light shuttles, will permit the shuttle to be always under a driving influence during its travel across the slay, will permit the manufacture of wide fabrics, and will obviate the disadvantages experienced in the previously proposed magnetically propelled shuttles.

In the broadest aspect of the invention a loom having a shuttle adapted to be moved by, and under continuous control of a traveller reciprocating underneath the warp threads, is characterised by the traveller being formed so as to provide a recessed seating for snugly receiving with warp threads interposed, a supporting part of the shuttle.

2

According to the invention in a narrower aspect, a loom having a shuttle adapted to be moved by, and under the control of, a traveller reciprocating underneath the warp threads, is characterised by the traveller having at least one pair of wheels forming between them a recessed seating for snugly receiving with warp threads interposed, a wheel supporting the shuttle.

In the above statement, and hereinafter in the specification and claims, the term "wheel" is not intended to exclude a roller, and also in the following description the term "roller" is not intended to exclude a wheel.

Preferably the pair of wheels project up above the slay, so that the warp threads are humped, to an extent controlled by auxiliary wheels adapted to run along the underside of the slay. The auxiliary wheels are preferably urged against the underside of the slay by an underneath pair of wheels running upon a supporting surface and resiliently pulled towards each other.

The slay is preferably a hollow structure having an upper part providing a gap through which the traveller's pair of wheels project and providing under surfaces on each side of the gap for the auxiliary wheels to run along. The bottom part of the structure may provide the supporting surface for the said underneath pair of wheels.

Guiding means may be located above the shuttle, at least over the end portions of the shuttle travel, so as positively to constrain the shuttle supporting part to nest in the recessed seating provided by the traveller. The traveller and the shuttle may comprise magnetically attracting means urging the shuttle supporting part to nest in the recessed seating provided by the traveller.

The traveller is preferably reciprocated with a simple harmonic motion, which may be produced by means of a Scotch yoke rotating a wheel about which is entrained a belt whose ends are connected to the traveller.

The invention is illustrated by way of example in the accompanying drawings, in which:

Figure 1 is a front elevation on an enlarged scale of a mechanism for producing the simple harmonic reciprocating motion of the traveller.

Figure 2 is a front elevation of part of a loom showing the slay and means for reciprocating the traveller.

Figure 3 is an end elevation of Figure 1.

Figure 4 is a front sectional elevation of the shuttle and traveller shown in position on the slay of loom.

Figure 5 is an end sectional elevation of Figure 4.

Referring to Figure 1, a shaft 1 is caused to rotate with constant angular velocity by suitable means (not shown) secured to the shaft 1 is a disc 2 which carries rigidly attached, a pin 3. A block member 4 is rotatably mounted on the pin 3 and is adapted to slide in a slot 5 formed in a cross head 6. The cross head 6 is formed integrally with rods 7 and 8 projecting respectively from either side thereof, which rods are supported in bearings 9 so that they are free to move only in an axial direction. It will be seen that rotation of the shaft 1 will cause the rods 7 and 8 to reciprocate axially according to a simple harmonic law. The mechanism just described is widely known by the name Scotch yoke.

The rod 8 has a thickened portion 10 in which rack teeth 11 are formed and engage with similar teeth 18 formed on a pinion 13, which is rigidly secured on the axle 14 of a wheel 15 of larger diameter, the axle being supported in suitable bearings (not shown). It will be seen that by means of the Scotch yoke mechanism described above the wheel 15 will rotate alternatively to the right and to the left through the rack 11 and pinion 13 and that its reversal will obey a simple harmonic law.

Referring to Figures 1, 2 and 3 a flexible wire or band 16 is passed around the wheel 15 several times, the wire being secured to the wheel by suitable means (not shown) in order to prevent slip, and then passes around four

idler wheels 17 identically formed which are situated two at each end of a hollow square sectioned loom slay 18 forming a shuttle race-board 19. The wire or band passes along the inside of the hollow slay 18 and is secured to a traveller generally indicated at 20 which is mounted within the slay so that it is free to reciprocate in a plane parallel to the slay 18 and race-board 10. It will be seen that the traveller 20 will reciprocate according to a simple harmonic law, and that the amplitude of its oscillations may conveniently be adjusted by selecting a suitable radial distance between the shaft 1 and the pin 3 and a suitable ratio of diameter of the wheel 15 to the pinion 13.

The hollow slay 18 is supported in conventional manner by slay swords 26, Figures 2 and 3, which pivot about a point Z at the intersection of two centre lines A and B. The point P on the periphery of the wheel 15 and the wire or band 16 extending therefrom are arranged to be in line with the pivotal point Z so that the slay may pivot without altering the effective length of the wire or band 16 although the wheel 15 remains in a fixed plane. The object of the pivoting of the slay is to allow the reed shown at 26a to beat up the weft threads (not shown) in the usual way during weaving. Apart from the modifications just described the general construction and layout of the slay is in accordance with normal practice.

Referring now to Figures 4 and 5 the traveller generally indicated at 20 consists of two longitudinal plates 21 spaced apart from each other so as to receive between them four wheels 22 positioned two at each end of the plates 21. The wheels are mounted to transverse axles 23 (one only of which is shown in Figure 5) the ends of which are secured in the plates 21 and assist in maintaining the two plates in their spaced relationship. Auxiliary wheels 24 are mounted on stub-axles 25 secured to the outside of each plate 21 co-axially with each of the wheels 22. The auxiliary wheels are free to rotate independently of the wheels 22.

The slay 18, as previously stated, is a hollow structure of square section in which the traveller 20 is mounted for reciprocation, and the upper surface or raceboard 19, of the slay has a longitudinal gap 27 (Figures 3 and 5) therein extending throughout the length of the slay, through which the wheels 22 of the traveller mounted in the slay are adapted to project. The extent of projection of the wheels 22 through the gap is controlled by the auxiliary wheels 24 which are adapted to run along the underside of the raceboard 19 as clearly shown in Figure 5. The auxiliary wheels 24 are urged upwardly against the underside of the raceboard 19 by two pairs of rollers 28 which are positioned one pair underneath each pair of traveller wheels 22. Each pair of rollers 28 is adapted to run along the bottom inner surface or floor 29 of the slay 18, and the two wheels of each pair are resiliently and continuously pulled towards each other by means of two coiled tension springs 30 which have their ends secured to the projecting ends of two axles 31 on which the rollers 28 are mounted as clearly shown in Figure 4. It will be seen that the pull of the springs 30 will cause each pair of rollers 28 to act as wedges between the inner surface 29 of the slay bottom and the traveller wheels 22 thus pressing the auxiliary wheels 24 continuously against the underside of the raceboard 19.

Means 32 are provided for attaching the ends of the wire or band 16 to the traveller at each end thereof.

A shuttle 33, adapted to be moved by and under the control of, the traveller 20, is provided with two rollers 34 each mounted within the shuttle body on an axle 35. Each of the rollers is shown as having a diameter equal to that of the traveller's wheels 22, but it will be appreciated that this is not a necessity and the ratio of the diameters of the rollers 34 and wheels 22 may be so selected as to make for a convenient ratio between the horizontal and vertical components of the accelerating force. The rollers 34 are so positioned in the shuttle body that when the shuttle

is placed upon the raceboard 19 immediately over the traveller 20, each roller will enter respectively the recessed seating formed between one of the pairs of traveller's wheels 22 mounted at each end of the traveller and fit snugly therein.

It will be seen from Figure 4 that a part of the shuttle body at each end is cut away on its underside so as to accommodate the portions of the wheels 22 projecting above the raceboard 19, and also so that a greater portion of each roller 34 projects from the shuttle body.

The shuttle is provided with a pair of soft iron armatures 36 positioned in the lower part of its body which are adapted to co-operate with a pair of horseshoe magnets 37 carried by the traveller 20 so as to complete a magnetic circuit. A small air gap 38 is left between the armatures and magnets to allow the free passage between them of warp threads indicated by a dotted line 39 in Figure 4.

The shuttle is equipped with the usual arrangements for carrying the cop or package of weft together with the usual means for guiding the thread out of the shuttle, but these are not shown so as to avoid confusion in the drawings.

The operation of the mechanism will now be described. Let it be supposed that the traveller is moved to the right in Figure 4 of the drawings, under the influence of the wire or band 16 functioning as previously described. The rollers 28 will be rotated in a clockwise direction by virtue of their frictional adhesion with the inner surface 29 of the bottom of the slay. This rotational movement will cause the traveller's wheels 22 to rotate in an anti-clockwise direction by virtue of their frictional adhesion with the rollers 28. This in turn will cause the shuttle rollers 34 to rotate in a clockwise direction due to their frictional adhesion with the traveller's wheels 22, and the shuttle will move to the right keeping its position above the traveller. The weight or mass of the shuttle imposes a definite frictional grip between the shuttle rollers and the traveller's wheels and this frictional grip is magnified by the magnetic attraction of the armatures 36 and magnets 37.

The line of warp threads indicated by the dotted line 39 pass between the shuttle rollers 34 and traveller's wheels 22. Because of the fact that at any instant a point at the top of each traveller's wheel 22 is stationary with respect to the warp threads under which each wheel is immediately passing, the warp threads pass between the rollers 34 and wheels 22 without being disturbed in a lateral direction. In a vertical direction, however, they are lifted a small amount equal to the extent to which the traveller's wheels 22 project above the slay. It may be mentioned that the points of contact of the shuttle rollers 34 with the traveller's wheels 22 are not completely stationary with respect to the warp threads, there being a very slight horizontal component of velocity. This component, however, is not sufficient in practice to effect the warp threads in a lateral direction by any measurable amount.

When the traveller and the shuttle reach the limit of their travel to the right in Figure 4, their movement is immediately reversed and the wheels 22, auxiliary wheels 24, rollers 28 and 34 will rotate in the opposite directions to those described as the traveller and shuttle move to the left across the slay.

As the traveller and shuttle oscillate across the slay together in accordance with a simple harmonic law, their acceleration will be at a maximum when they are at the limit of their travel at one or the other end of the slay 18, the magnitude of this acceleration being dependent upon the square of the number of oscillations per unit of time. At this point in their movement there is a tendency for the shuttle to continue its movement away from the center of the slay and to resist the force of the magnetic attraction of the armatures 36 and magnets 37 to reverse its direction of travel and accelerate it back towards the center of the slay.

If the value or magnitude of the force accelerating the shuttle exceeds the force available to hold the shuttle to the traveller, the shuttle will obviously leave its position over the traveller and it will cease to follow the movements of the traveller. However, in order for this to happen the shuttle must rise a little to clear the projecting portions of the traveller's wheels 22 and this action must increase the air gap 38 between the armatures 36 and magnets 37. The magnetic attraction between the armatures 36 and magnets will resist the tendency of the shuttle to rise from its position on the traveller, and will impart to the shuttle a horizontal acceleration force. The magnetic flux is stressed in tension instead of in shear as has previously been proposed, and this stressing in tension has been found in practice to be far more effective than the usual way of stressing the magnetic flux in shear.

In order to assist the magnetic attraction of the armatures 36 and magnets 37 to hold the shuttle on to the traveller at the points of reversal of their direction of travel, there may be arranged guiding means located over the end portions of the slay to positively constrain the shuttle to maintain its position on the traveller with its rollers 34 nesting in the recessed seatings formed by the traveller's wheels 22. Such a guiding means is shown in Figure 4 and takes the form of a number of rollers or wheels 40 rotately mounted in a frame 41 secured by suitable means (not shown) over the slay at a height sufficient for the rollers or wheels to be effective in their constraining action, without retarding the travel of the shuttle.

The armatures 36 and magnets 37 are not absolutely essential, but if not carried by the shuttle and traveller respectively, it would be necessary to have a top guide such as described located above the full length, or most of the length of the slay.

In practice the traveller's wheels 22 may be made to project an amount sufficient for the shuttle rollers 34 to rest lightly on the raceboard 19 on either side of the gap 27.

Since the rate of shuttle travel is relatively slow, it is necessary that the normal beat-up of the slay shall be modified to allow the shuttle sufficient time to move through the shed. This may be achieved either by means of cams with suitable dwells, or by means of a crank and connecting rod such as is commonly used in looms, but with the connecting rod only slightly longer than the radius of the crank so as to produce the desired period of dwell.

It will be appreciated that with the improved construction of shuttle motion according to the invention, if armatures and magnets are used, only very light magnets need be provided. Another advantage is that as the shuttle is firmly held onto the traveller, there is no relative vibration between the two.

In addition to being practically noiseless, a loom having the improved shuttle motion is capable of weaving fabrics of unlimited width, and since the shuttle does not dwell at the limit of its travel across the slay, a very high rate of working may be achieved in spite of the low value of maximum velocity of the shuttle.

What is claimed is:

1. In a loom the improvement comprising, a slay comprising a raceboard positioned below and extending across the warp threads and a floor spaced below said raceboard, said raceboard having a longitudinal gap extending the width of the warp threads, a traveler mounted in the slay for reciprocating movement from one side of the warp threads to the other, said traveler having a front and a rear pair of wheels projecting through the gap of the raceboard, the wheels in said pairs being slightly spaced from one another with their axes extending transversely of the slay in substantially the same horizontal plane, a front and a rear pair of rollers arranged to roll longitudinally along the floor of the slay, the rollers of each of said

pairs being spring urged together and supporting a corresponding pair of said spaced wheels between them, auxiliary wheels axially fixed on said traveler urged against the underside of said raceboard by the springs of said pairs of rollers acting through the spaced wheels of said traveler, and a shuttle above the warp threads mounted on a front and a rear roller, each of said shuttle rollers being supported by and nesting with a corresponding pair of spaced wheels of said traveler, whereby the traveler supports the shuttle with warp threads interposed and the shuttle moves with the traveler in a reciprocating manner.

2. The improvement in a loom according to claim 1, wherein the traveler and the shuttle contain magnetically attracting means.

3. In a loom the improvement comprising, traveler guide means spaced below and extending across the warp threads, a traveler mounted on rollers in contact with said guide means for reciprocating movement from one side of the warp threads to the other, said traveler comprising a pair of wheels exposed to the warp threads and slightly spaced from one another with their axes transverse to the slay, said rollers comprising a pair of rollers spring urged together and adapted to support said pair of wheels between them, the tendency of said pair of rollers being to come together and lift said pair of wheels into the warp threads, means for preventing said pair of wheels from rising above a set level with respect to the warp threads, and a shuttle above the warp threads mounted on rolling means, said rolling means comprising a roller supported by and nesting with the pair of spaced wheels of said traveler, whereby the traveler supports the shuttle with warp threads interposed and the shuttle moves with the traveler in a reciprocating manner.

4. The improvement in a loom according to claim 3, wherein the traveler and the shuttle contain magnetically attracting means.

5. In a loom the improvement comprising, a slay comprising a race board positioned below and extending across the warp threads and a floor extending below said race board, said race board having a longitudinal gap extending the width of the warp threads, a traveller in the slay mounted on a pair of rollers in contact with said floor for reciprocating movement from one side of the warp threads to the other, said traveller having a pair of spaced wheels projecting through the gap of the race board and auxiliary rolling means in contact with the underside of the race board, said pair of wheels being supported between said pair of rollers and said rollers being spring urged together whereby said pair of wheels is urged upward as the rollers tend to come together and said auxiliary rolling means constrain said pair of wheels from further upward movement, and a shuttle above the warp threads mounted on rolling means, said shuttle rolling means being supported by and nesting with the spaced wheels of said traveler, whereby the traveller supports the shuttle with warp threads interposed and the shuttle moves with the traveller in a reciprocating manner.

6. In a loom the improvement comprising, traveller guide means spaced below and extending across the warp threads, a traveller mounted on rollers in contact with said guide means for reciprocating movement from one side of the warp threads to the other, said traveller comprising a pair of wheels exposed to the warp threads and slightly spaced from one another with their axes transverse to the slay, said rollers comprising a pair of rollers resiliently urged together and adapted to support said pair of wheels between them, the tendency of said pair of rollers being to come together and lift said pair of wheels into the warp threads, means for preventing said pair of wheels from rising above a set level with respect to the warp threads, and a shuttle above the warp threads mounted on rolling means, said rolling means comprising a roller supported by and nesting with the pair of spaced wheels

of said traveller, whereby the traveller supports the shuttle with warp threads interposed and the shuttle moves with the traveller in a reciprocating manner.
